UNITED STATES PATENT OFFICE.

GUSTAV FRIEDRICH GIEHLER, OF CHEMNITZ, GERMANY.

LOOM.

Application filed June 6, 1925, Serial No. 35,392, and in Germany August 26, 1924.

This invention relates to a loom of the type shown in British Patent No. 151,270 wherein the implements used for the weaving, such as shuttles, skewers and the like, 5 on their run through the shed, are guided by members which are supported on the lathe or batten and enter the shed for the time of the run of the shuttle or the like.

In order to render possible the entrance 10 of these guiding members into the shed and to guard, as far as possible against an injurious influencing of the warp threads by the said members, projections in the form of right-angled triangles have hitherto been 15 fitted to the lathe, these projections penetrating between the threads of the upper and lower sheds before the attainment of their maximum distance from one another, and these projections have been so distributed 20 that on one side of each triangle a space is left, free from threads, through which the guiding members enter the sheds. These contrivances were rather complicated, and, owing to the said triangular projections 25 on the lathe acting on the warp threads there was a non-uniform and not altogether harmless stressing of the warp threads.

According to the present invention the 30 contrivance is so arranged that the lathe projections for producing the passage spaces free from warp threads for the entrance of the shuttle and like guiding members are no longer necessary. The guiding members are so constructed and so moved that they 35 can enter between the warp threads of the upper and lower sheds running in the usual manner and are so moved laterally, that is in the direction of the shuttle race, that during the shed-forming movement of the warp 40 threads they do not act unfavourably on the latter, as they move out of the way of the warp threads moving up or down in forming sheds. The members that form the 45 guiding tracks of the shuttle or the like are then in themselves of a simpler kind, and the same remark applies to the members that move and guide them.

The guiding members themselves are in 50 the form of straight pegs or pins, which rest in guides so as to be displaceable in their longitudinal direction by plates arranged on the lathe, which in their turn are so mounted on the lathe as to be reciprocable in the longitudinal direction thereof.

55 One constructional example of the sub-

ject-matter of the invention is illustrated in the accompanying drawing, wherein—

Figure 1 shows a partial front elevation, 60 Figure 2 a corresponding plan, and

Figure 3 a cross-sectional view illustrating three characteristic lathe positions.

To the lathe is secured an angle iron 1, which will hereinafter be designated the lathe. On the vertical lathe 1 are supported individual plates 3. They each engage with slots 4 over two screws 5 mounted on the lathe, so that with their slots they can slide backwards and forwards thereon. The amplitude of the reciprocating motion employed in the present case is given by the 70 dimensions indicated at *a* in Figure 1. The individual plates 3 are connected with one another by coupling members 7. A rod 8, which is connected with any movable part of the loom, moves the coupled plates 3 75 backwards and forwards by the amount *a*. On each plate is arranged a slot guide 10, in which rests a corresponding profile bar 11, which merges at its upper end, according to Figure 1, into the peg-like guide 12 80 for shuttles or the like. The slot guide, and with it the peg 12, are at an angle of about 45° to the horizontal, and each peg 12 is flattened off at the top so as to form an edge 85 at 13, which facilitates penetration between the warp threads of the lower shed. The contrivance is only illustrated for the lower shed; but obviously it is also provided in the same manner for the upper shed, but turned of course in the reverse direction.

On the guiding member 11 of each guiding peg 12 there engages, on a pivot 15, a short connecting rod 16, which is mounted on the pivot pin 17 of a crank 19, journaled at 18 on the plate 3. The crank pins 90 17 of all the plates 3 are coupled to one another by a common rod 20. The rod 20 is moved by any suitable means in a similar manner to the rod 8.

If the rod 20 moves to the right, in the 100 sense of Figure 1, all the cranks 19 swing in a clockwise direction, and their connecting rods 16 move the guiding pegs 11, 12 out of the chain-dotted positions *b* into the full-line highest positions *c* and guide them, during the reversed swinging of the cranks 19, back into the positions *b*. Owing to the movement of the rod 8, the ground plates 3, which carry the guiding pegs 11, 12, and which may also be united to the number of 110

several, are reciprocated by the amount a , so that the guiding pegs 12 travel backwards and forwards between the positions c and c' , in so far as they remain during 5 the movement of the plate 3 in the highest position as illustrated.

Now during the shed-formation the lathe 1 moves backwards and forwards, B in Figure 3 showing a mid position while A and C 10 show the terminal positions. During the lathe movement from A to C the warp threads k^1 and k^2 of course stand still, as they always allow the swinging movement required for the shed-forming to finish. If 15 in the lathe position A the blade or reed p has beaten up, the guides 12, when the lathe swings to the left, must pass between the warp threads, in order to serve, in about the position C, in the case of the maximum 20 shed opening, as a guide for the shuttle. The warp threads of the two sheds move upwards and downwards during the swinging of the lathe, and in order that they may not be hindered during this motion by the 25 oblique pegs 12, and may not rub against them, the reciprocating movement of the plates 3 carrying the pegs 12, as well as the reciprocating movement of the pegs 12, is effected by the means set forth above. If, 30 when the shed opens the warp threads k^2 are moving downwards, the threads indicated at k^3 on the right of Figure 1 would come into contact with the guiding peg 12 introduced there into the shed and they 35 would slide downwards along its left-hand oblique surface, that is, they would be deflected towards the left out of their vertical path of motion. This is prevented by means of the contrivances set forth, owing to the 40 fact that at the same time the carrying plate 3 of the peg 12 moves away to the right, so that the left-hand oblique lateral surfaces of the peg 12 always move out of the way towards the right just so far that the descending 45 threads at k^3 can move without hindrance. In that case the oblique peg 12 slides with its right-hand side to a certain extent over the warp threads k^4 located there without being able to affect them adversely. 50 If the warp threads previously located in the position k^3 have then, in the course of the shed opening, reached the similarly drawn position k^3' , the guiding peg 12 has then passed into the chain-dotted position; 55 upon the change of direction of the warp movement the change of direction in the movement of the plate 3 also occurs, so that the warp thread adjacent to the guiding peg 12 for the time being in turn remains immediately adjacent to the oblique side of the 60 guiding peg, without disturbing friction or the like being able to occur.

For the guiding device set forth it is not a condition that the guides 12 should consist of straight bodies. They might be 65

curved instead. The reciprocating movement of their carriers 3 would then have to be so timed that the guides, during the shed-formation and during their movement within the warp threads, do not disturb the latter in their movement. The construction of the moving mechanisms however is of course simpler in the case of a straight formation of the guides. 70

What I claim is: 75

1. A loom comprising weaving implements adapted to pass through a shed formed by shifting some of the warp threads in one direction and some in another, guiding bodies for said implements, laterally reciprocable carrier plates, said guiding bodies being mounted on said carrier plates, and the movements of said carrier plates being so timed that said guiding bodies move out of the way of the warp threads as said warp threads are shifted to form sheds. 80

2. A loom comprising weaving implements adapted to pass through a shed formed by shifting some of the warp threads in one direction and some in another, rectilinear peg-like guiding bodies for said implements, and laterally reciprocable carrier plates formed with oblique slot guides adapted to support said guiding bodies. 90

3. A loom comprising weaving implements adapted to pass through a shed formed by shifting some of the warp threads in one direction and some in another, guiding bodies for said implements, laterally reciprocable carrier plates, said guiding bodies being mounted on said carrier plates, the movement of said carrier plates being so timed that said guiding bodies move out of the way of the warp threads as said warp threads are shifted to form sheds, and crank mechanisms coupled to one another for reciprocating the guiding bodies relatively to the carrier plates on which they are mounted. 100

4. A loom comprising weaving implements adapted to pass through a shed formed by shifting some of the warp threads in one direction and some in another, a swinging lathe, peg-like guiding bodies capable of moving in a straight line for the weaving implements, laterally reciprocable carrier plates formed with oblique slot guides adapted to support said guiding bodies, means for so timing the movements of said carrier plates that said guiding bodies move out of the way of the warp threads during the oscillations of the lathe as said warp threads are shifted to form sheds, and crank mechanisms coupled to one another for reciprocating the guiding bodies relatively to the carrier plates on which they are mounted. 110

In testimony whereof I have signed my name to this specification.

GUSTAV FRIEDRICH GIEHLER.
